UNITED STATES PATENT OFFICE.

GEORGE A. GREGERSON AND FRED O. GREGERSON, OF ROCHESTER,
MINNESOTA.

DESIGN FOR A HARNESS-EYE.

SPECIFICATION forming part of Design No. 25,710, dated June 30, 1896.

Application filed May 7, 1896. Serial No. 590,624. Term of patent 14 years.

To all whom it may concern:

Be it known that we, GEORGE A. GREGERSON and FRED O. GREGERSON, citizens of the United States, residing at Rochester, in the county of Olmsted and State of Minnesota, have invented a certain new and useful Design for Harness-Eyes, of which the following is a specification, reference being had therein to the accompanying drawing.

- 10 The leading feature of our design consists of a plate formed into a transverse oblong loop *a*, having projecting from its rear bar a flat tongue *b*, which is narrower and thinner than the loop and is provided with a central longitudinal slot *b'*, running transversely to the loop. Formed integral with the front bar of the loop is another loop *c*, which extends at right angles to the loop *a* and which is

rounded off at its forward end and gradually thickened toward that end, as at *c'*. The bar 20 of the loop is rounded at its edges, as shown, and the opening through the loop comes to a point, as *c²*, near the loop *a*. The edges of the bars of the loop *a* are also rounded and curved. 25

Having described our invention, what we claim is—

The design for a harness-eye substantially as herein shown and described.

In testimony whereof we affix our signatures in presence of two witnesses.

GEORGE A. GREGERSON.
FRED O. GREGERSON.
